Patented Nov. 3, 1908.

FIG. 3.

UNITED STATES PATENT OFFICE.

GUSTAF AXEL MAURITZ AGRELL, OF STOCKHOLM, SWEDEN

TYPE-PRINTING-TELEGRAPH APPARATUS.

No. 902,792.

Specification of Letters Patent.

Patented Nov. 3, 1908.

Application filed January 3, 1908. Serial No. 409,765.

To all whom it may concern:

Be it known that I, GUSTAF AXEL MAURITZ AGRELL, a subject of the King of Sweden, and resident of Handverkaregatan 36, Stockholm, in the Kingdom of Sweden, have invented certain new and useful Improvements in Type-Printing-Telegraph Apparatus, of which the following is a specification, reference being had therein to the accompanying drawing.

This invention relates to improvements in telegraph apparatus of the class, which operate with a movable type wheel and are adapted preferably to convert telegraph signs into types on a strip or sheet of paper by means of electric impulses of different force or polarity.

The object of the invention is to provide means for moving the said type wheel to the printing position and then to a certain starting position, after the type has been printed.

The invention is illustrated in the accompanying drawing.

Figure 1 shows partly in a side view and partly in section the means for operating the type wheel. The said figure also shows the type wheel, several electro magnets, relays and electric connections belonging to the apparatus. Fig. 2 shows the printing wheel and the operating disks in an evolved state. Fig. 3 is a side view of the catching mechanism of the apparatus. Fig. 4 is a section and Fig. 5 a side view of another form of the disks by means of which the type wheel is operated. Fig. 6 shows three operating disks in an evolved state.

On a shaft 4, journaled in the frame 5 of the apparatus and rotated continually by a spring, an electric motor or the like in the direction indicated by the arrow α , a tube 6 is threaded, to which are fixed the type wheel 7, a star-wheel 8 and a disk 3. In the right hand side of the said disk 3 a recess is provided, containing a friction disk 13, which by a pin 9, fixed in the shaft 4 and engaging the disk 13, is caused to rotate with the shaft. The friction disk 13 is slidable on the shaft and forced against the disk 3 by means, described below, and consequently tends to bring with it the said disk and the type wheel 7. At the right hand side of the friction disk 13 two disks 2 and 1, which are provided with teeth on their peripheral surfaces and each contain a friction disk 12 and 11 respectively of the same type as the disk 13, are mounted on the shaft 4 in a slidable man-

ner but caused to rotate with the same. A spiral spring 10, mounted on the shaft 4, acts against the disk 11 and forces the disks 11, 1, 12, 2, 13 and 3 against each other. The pressure of the spring 10 can be adjusted by a nut 14 and a jam nut 15, screw threaded on the shaft 4. A ring 38, fixed on the shaft, prevents the type wheel and the said disks from moving toward the left. Pins 16 and 17 project from the left side of the disks 1 and 2 respectively and coöperate with pins 18 and 19, projecting from the right side of the disks 2 and 3 respectively in such manner, that, if for instance the disk 1 is stopped in a certain position, by the catch mechanism described below, the disk 2 can be rotated only until the pin 18 strikes the pin 16, and the disk 3, until the pin 19 strikes the pin 17. Consequently, the type wheel occupies a certain position with relation to the disk 1 and if the disk 1 is permitted to rotate for a certain distance, the type wheel will rotate the same distance. If, instead of the disk 1, the disk 2 is stopped by the said catch mechanism, the type wheel will, evidently, be dependent of the disk 2 as for the rotary movement, whereas the free disk 1 continues in its rotary movement, until it is stopped in a position, nearly coinciding with its starting position, in the manner stated below.

The disks 1 and 2 are shown in Fig. 2 in an evolved state and in the starting position, with relation to each other. The disk 2 is twice as wide as the disk 1 and provided with two rows of teeth, so located, that if one of the rows is thought moved side wise, so that its teeth enter the spaces between the teeth of the other row and the teeth form only one row together, a toothed wheel of the ordinary type is gained. At the left hand side of the disks 1 and 2 the type wheel 7 is shown also in an evolved state. Each of the types of the said wheel is located opposite to the tooth of the disk 2, which finally determines the position, which the type wheel occupies, as the corresponding sign is to be printed. Consequently, if for instance the letter N is to be printed, the disks 1, 2 and the type wheel 7 must be permitted to rotate, so that the tooth 25 is stopped, which is effected by the catching mechanism, which, as the disks are in the starting position, engages the "starting tooth" 20, but can be moved side wise, so that it coöperates with the different rows of teeth.

In order to illustrate the manner in which

the catching mechanism coöperates with the disks 1 and 2, one may think that the surfaces of the said disks and the type wheel are located in a stationary plane and that the catching mechanism can be moved from the tooth 20 in two directions indicated by the arrows *y* and *z* in Fig. 2, *i. e.*, partly from row to row, partly in each row from tooth to tooth, and that the spot on the paper, on which the sign is to be printed, moves with the catching mechanism, when moved from tooth to tooth in the same row. Each movement of the catching mechanism side wise is effected by emitting from a transmitting apparatus one kind of impulses (as for instance +150 volts) and each movement of the mechanism from tooth to tooth of the rows respectively by the emitting of another kind of impulses (as for instance +50 volts). In order that the sum of the said impulses may be as small as possible, they may for the present case be so combined that the catching mechanism is moved from the tooth 20 and successively to the teeth 21, 22, 23, 24 and 25, consequently five impulses. During the movement last mentioned from 24 to 25, which in fact was a movement side wise in the direction of the arrow *y*, also a movement in the direction of the arrow *z* is, obviously, effected, because the catching mechanism is always moved in the direction last mentioned, as soon as it is moved from the right row to the left one on the disk 2. As the spot on the paper, on which the letter is to be printed, has followed the catching mechanism, when moved in the direction indicated by the arrow *z*, it will, consequently, now be opposite the letter *N*, and by emitting a third kind of impulses (as for instance -150 volts) a copy of the letter *N* on the paper is effected at first, other operations being then also effected.

If the letter *y* is to be printed, the catching mechanism is moved from the tooth 20 to the teeth 26, 27, 28, 29 and 30, and so on. The said catching mechanism preferably consists of two rods or catches 31, 32, Figs. 1 and 3, slidably mounted in a slide 33. As an electro magnet 68 is energized, it attracts its armature fixed on a lever 34, which is pivoted at 36 to the frame of the apparatus and is acted upon in the opposite direction of a spring 34^x. The said lever 34 is by a pin 34¹ passing through a notch in the rod 31, connected with the said rod, so that the latter is pushed into one of the spaces between the teeth of the disks 1 and 2 respectively. The other rod 32 is acted upon by a two armed lever 35, which is pivoted at 37 to the frame of the apparatus and by a pin 35¹ engages a notch in the rod. The said lever 35 is by a slot provided in the same and a pin 35^x fixed in the lever 34 connected with the latter, so that the rod 32 is

withdrawn from the teeth of the disks 1 and 2 respectively, when the rod 31 is lowered into engagement with the same. Owing to the said reciprocal action of the catching rods 31, 32 the disks 1 and 2 will be rotated through a greater or shorter distance depending on the different distances between the teeth of the rows. The slide 33 can be moved on a rod 39, square in cross section and fixed in the frame 5 of the apparatus, by an electro magnet 40, which, attracting its armature, acts upon a lever 41 against the action of a spring 41^x, which lever is pivoted at 42 to the frame of the apparatus and by a pin 44 connected with a catch 43, 80 adapted to engage one of the teeth 33¹, 33¹¹, provided on the upper side of the slide 33, as the armature is attracted, so that, as the said armature is released, the slide 33 is moved one tooth toward the left by the 85 spring 41^x. A catch 45, pivoted at 46 to the frame of the apparatus, prevents the slide 33 from moving with the catch 43, when the same, returned to its original position, slides over the tooth 33¹¹. As the slide 33 90 is moved end wise one or two teeth, the rods 31 and 32 are also moved in the same direction by the slide and, consequently, are brought to coöperate with the first or second row of teeth on the disk 2. 95

As an electro magnet 47 is energized and attracts its armature against the action of a spring 47^x, the arm 48¹ of a three armed lever 48, 48¹, 48¹¹, pivoted at 48^x to the frame of the apparatus, is swung upward. The 100 said arm 48¹ is provided with a tooth 49 and a head 50, acting like a hammer. As the arm 48 is swung upward, the said tooth engages the star-wheel 8 and holds the type wheel 7 in its position, whereupon the hammer 50 forces the paper *a* against the type, provided with ink in any suitable manner, so that a copy of the said type is gained. At the same time the vertical arm 48¹¹ is 105 swung toward the right. During the said 110 movement the tip of the arm 48¹¹ acts upon cam shaped projections 52, 53 on the lower sides of the catches 43, 45 and raises the said catches, so that they are brought out of engagement with the slide 33. The arm 48¹¹ 115 then moves the slide toward the right, so that the rods 31 and 32 will again coöperate with the disk 1.

The slide 33 has a projection 54, which extends along the slide and, as the slide is 120 moved toward the left from the position shown in the drawing, is placed in the path of an arm 55, projecting from the right side of the disk 1, so that the said disk, disengaged from the rods 31 and 32, as the same 125 are moved side wise can rotate only until the arm 55 strikes against the projection 54. The disk 1 has then been rotated nearly to its starting position, so that, when the slide is forced backward toward the right and, 130

consequently, the projection 54 ceases to hold the disk 1, the latter is rotated, until the "starting tooth" 20 strikes against the rod 32. The arm 55 then passes by the projection 54 for such a distance, that it is out of the path of the same. As the rods 31 and 32 are moved from the disk 2 to the disk 1, the disk 2 is disengaged and, consequently is rotated, until the pin 18 strikes against the 10 pin 16. Also the disk 2 has then been rotated to its starting position.

As the impulse of -150 volts is interrupted, the armature of the electro magnet 47 and the lever 48, 48¹, 48¹¹ return to their 15 normal positions, so that the hammer 50 is moved from the type-wheel 7. The paper *a* is then fed a suitable distance and the tooth 49 disengaged from the star-wheel 8, so that 20 also the type-wheel and the disk 3 can rotate to their starting position, *i. e.*, until the pin 19 strikes against the pin 17. The arm 48¹¹ is at the same time swung toward the left, so that the catches 43 and 45, made free, fall down on the slide 33. Consequently, the apparatus 25 is now again ready for effecting the printing of the next sign.

The electro-magnets 40, 47 and 68 may be energized by the current of a local battery 56 by the armatures 57 and 58 of two line 30 relays 59 and 60, which armatures are caused to shift position by the action of the line current. The relay 59 is so polarized, that negative currents force the tongue piece 61, to which the armature 57 is fixed, against 35 a contact piece 62, and positive currents force the said tongue piece against contact pieces 63 and 64. The relay 60 is unpolarized and the armature of the same is held in the normal position, shown in the drawing, 40 by a spring 65, the tension of which is so adjusted, that the electro magnet, when energized by a current of 50 volts, does not attract the armature, but the armature is attracted only when a current of 150 volts, 45 either $+150$ or -150 , passes through the electro magnet. Owing to the said arrangement the armature or tongue piece 58 bears against a contact piece 66, when the tension of the line current is 50 volts and against a 50 contact piece 67, when the tension of the said current is 150 volts. If for the energizing of the said three local electro-magnets currents of $+50$, $+150$ and -150 volts are used, as stated before, impulses of -50 volts 55 are preferably used for returning the armature 57 of the polarized relay 59 to its normal position, and, thus, the said impulses fill up the intervals between the impulses of $+50$, $+150$ and -150 volts. Consequently, 60 if an impulse of -50 volts is emitted from a transmitting apparatus, the armatures of the relays 59 and 60 occupy the positions shown in the drawing and all electro-magnets are inoperative. If an impulse of $+50$ volts 65 passes through the relays, only the relay

59 is caused to operate and the current passes from the local battery 56 through the tongue piece 61, the contact piece 63, the electro-magnet 68, the contact piece 66 and the tongue piece 58 back to the battery. 70 If the line current is of $+150$ volts, both the relays are caused to operate and the current passes from the local battery 56 through the tongue piece 61, the contact piece 64, the electro-magnet 40, the contact piece 67 and the tongue piece 58 back to the battery. If, finally, the line current is of -150 volts, only the relay 60 is caused to operate and the current passes from the local battery 56 through the tongue piece 61, 80 the contact piece 62, the electro-magnet 47, the contact piece 67 and the tongue piece 58 back to the battery.

In the form of the type wheel operating disks shown in Figs. 4 and 5 each of the said 85 disks is acted upon by a coil spring 69, 69¹ respectively only two disks 70, 70¹ being shown. One end of the spring 69 is fixed to the disk 70, corresponding to the disk 1 in Fig. 1, by means of a screw 71, the other end 90 of the said spring being fixed to the shaft 4 by means of a screw 72. The spring 69¹ is fixed to the disk 70¹ and the shaft 4 in the same manner. As the said shaft 4 is rotated 95 by a motor for instance, connected with the shaft by a friction clutch (the said motor and clutch being not shown in the drawing), the tension of the springs is increased and, when increased to a certain degree, it overcomes the friction between the members of 100 the clutch, so that the shaft 4 is stopped and remains stationary until the tension of one of the springs is decreased at the momentary disengagement of the corresponding disk. The said disk will then be rotated by the 105 spring. The disks are stopped in their rotary movement by means of teeth 73 on their periphery and a catching mechanism, which may be constructed as shown in Fig. 1. 74 is an arm corresponding to the arm 55 in Fig. 1. The disks 70, 70¹ are provided with projections 75, 76 co-operating in the same manner as the projections 16 and 18 in Fig. 1. The number of the type wheel operating disks 110 may be varied and is dependent upon the greatest number of impulses for moving the catching mechanism side wise, which may be used in the different combinations of currents. 115

Fig. 6 shows the most suitable grouping of the teeth on three disks (the central disk being provided with two rows of teeth), when decided that three impulses at most may be used for moving the catching mechanism side wise and the sum of impulses of 125 each combination may not be greater than five.

As seen from the above description, the type wheel may, by the operating mechanism described, be moved to each of the print- 130

ing positions by means of a small number of impulses. A further advantage consists in the apparatus being able to operate with great speed, owing to the fact that each operating disk, having functionated, is at once moved to its starting position, so that, as a sign has been printed, the operating mechanism is at once ready to move the type wheel to the position necessary for the printing of 10 the next sign.

Having now described my invention, what I claim as new and desire to secure by Letters Patent is:

1. In an electric type printing apparatus 15 the combination with the movable type wheel of a number of the said wheel operating members, rotatable with relation to each other and located at the side of each other, a catching mechanism, which coöperates with 20 the said members and through the effecting of a relative movement between the mechanism and the members longitudinally to the axis of the members is caused to coöperate with each of the members, means for transmitting 25 the movement of one of the outermost members of the row to the type wheel, and means connecting the members in such manner that, when one of the members is stopped, the member or members, which are 30 located at one side of the stopped member, remain in their position with relation to the stopped member, but the member or the members, which are located at the opposite side 35 of the stopped member, are independent of the same, so that they occupy their starting position.

2. In an electric type printing apparatus the combination with the movable type wheel of a number of the said wheel operating 40 members, rotatable with relation to each other and located at the side of each other, a catching mechanism, which coöperates with the said members and through the effecting of a relative movement between the mechanism and the members longitudinally to the axis of the members is caused to coöperate with each of the members, means for transmitting 45 the movement of one of the outermost members of the row to the type wheel, and coöperating projections on the said operating disks, substantially as described and for the purpose set forth.

50 means connecting the members in such manner that when one of the members is stopped, the member or members, which are located at one side of the stopped member, remain in their position with relation to the stopped

member, but the member or the members, 55 which are located at the opposite side of the stopped member, are independent of the same, so that they occupy their starting position, and means through which two different kinds of impulses emitted from a transmitting apparatus effect the said relative movement between the catching mechanism and the members, and the shifting of the catching mechanism, so that the member, just coöperating with the same, is permitted 60 to rotate.

3. In an electric type printing apparatus the combination with the movable type wheel of a number of the said wheel operating disks, loosely mounted on a rotating 70 shaft and provided with teeth on their peripheral surface, friction disks mounted between the said disks and slideable on the shaft longitudinally to the same, means for causing the friction disks to rotate with the 75 shaft, means for keeping all the disks in frictional contact with each other, a catching mechanism, means for moving the same into positions to coöperate with the operating disks respectively, means for transmitting 80 the movement of one of the outermost members of the row to the type wheel, and coöperating projections on the said operating disks, substantially as described and for the purpose set forth.

4. In an electric type printing apparatus the combination with the movable type wheel of a number of the said wheel operating disks, loosely mounted on a rotating 90 shaft and provided with teeth on their peripheral surface, coil-springs connected with the shaft and the disks respectively, a catching mechanism, means for moving the same into positions to coöperate with the operating disks respectively, means for 95 transmitting the movement of one of the outermost members of the row to the type wheel, and coöperating projections on the said operating disks, substantially as described and for the purpose set forth.

In witness whereof, I have hereunto signed my name in the presence of two subscribing witnesses.

GUSTAF AXEL MAURITZ AGRELL.
